(57) **CLAIM**

The ornamental design for a power bank, as shown and described.

DESCRIPTION

FIG. 1 is a front, right, top perspective view of a power bank, showing my new design;

FIG. 2 is a rear, left, bottom perspective view thereof;

FIG. 3 is a front elevational view of the enlarged scale thereof;

FIG. 4 is a rear elevational view of the enlarged scale thereof;

FIG. 5 is a left side view of the enlarged scale thereof;

FIG. 6 is a right side view of the enlarged scale thereof;

FIG. 7 is a top plan view of the enlarged scale thereof;

FIG. 8 is a bottom plan view of the enlarged scale thereof;

FIG. 9 is an enlarged view of detail 9 in FIG. 1; and,

FIG. 10 is an enlarged view of detail 10 in FIG. 2.

The dashed broken lines in the figures are for the purposes of illustrating portions of the power bank and form no part of the claimed design.

The dash-dot-dash broken lines are for notating enlarged views and form no part of the claimed design.
